RAZOR WITH STATIONARY BLADE AND MOVABLE SHEAR PLATE

Raymond Knapp, Forest Hills, N. Y.

Application January 30, 1956, Serial No. 562,223

4 Claims. (Cl. 30—43)

This invention relates to dry shavers and more particularly to a non-electric dry shaver.

It is an object of the present invention to provide a non-electric dry shaver which may be carried in one's pocket and which will shave the user without requiring electricity or soap and water or shaving lather.

It is another object of the present invention to provide a non-electric dry shaver which includes a grooved channel member which receives therewithin from either end an inner cutter which cooperates with a slotted cylinder rotatably mounted on the outside of said channel member, the stationary inner cutter cooperating with the rotating outer cutter to provide a cleaner, closer and quicker shave without requiring electricity or lather.

It is still another object of the present invention to provide a non-electric dry shaver of the above type wherein the inner cutter may be replaced from either end of the channel member and the cutter cylinder without disassembling any parts of the shaver.

It is still another object of the present invention to provide a non-electric dry shaver of the above type which includes an inner cutter having oppositely disposed blades which cooperate with the rotating outer cylinder to shave both on the up and down strokes, to provide a shave in one-half the time; in other words, to provide a non-electric dry shaver which shaves when moved in either direction.

It is still another object of the present invention to provide a non-electric dry shaver of the above type wherein the inner cutter blades cooperate with the inside surface of the slotted outer cylinder during rotational movement of the latter to provide a self-honing action whereby the blade edges are retained sharp and true over relatively long periods of time.

It is still another object of the present invention to provide a non-electric dry shaver of the above type wherein the inner cutter may be removed as a unit from either end of the channel and slotted cylinder to be replaced when worn by a new inner cutter unit without the necessity of handling the cutting edges of the inner cutter blades at any time and to prevent accidents thereby.

For other objects and for a better understanding of the invention, reference may be had to the following detailed description taken in connection with the accompanying drawing, in which:

Figure 1 is a perspective view of a preferred embodiment of the present invention;

Fig. 2 is an enlarged fragmentary vertical sectional view taken along the line 2-2 of Fig. 1 and showing the inner cutter unit about to be inserted into the grooved channel member through the open end of the outer cutter;

Fig. 3 is a transverse sectional view taken along the line 3—3 of Fig. 2;

Fig. 4 is an exploded perspective view of the parts comprising the invention; and Fig. 5 is a sectional view taken

Fig. 5 is a transverse vertical sectional view taken along the line 5—5 of Fig. 4; and

2

Fig. 6 is a view similar to Fig. 5 of a modified form of the present invention.

Referring now more in detail to the drawing and more particularly to Figs. 1 through 5, 10 represents a handle having a semi-circular side and bottom edge 11 and a flat straight upper edge 12, substantially as illustrated. The handle 10 may be formed of plastic, metal or other suitable material and is preferably hollow to reduce the weight thereof.

10 A pair of angle brackets 13 are mounted at opposite ends of the upper horizontal edge 12 by means of the countersunk screws 14 or other suitable fastening means.

15 A grooved channel member 15 having a segmental cylindrical outer surface is fixedly mounted between the angle brackets 13 by means of the internally threaded openings 16 provided at the ends thereof and the countersunk screws 17 positioned therein, the screws 17 passing through the openings provided in the angle brackets 13. The upper portion of the channel member 15 is cut away 20 (Fig. 3) to reveal a rectangular inner opening 18 which communicates at its upper edges with the grooves or tracks 19 provided along the opposite sides interiorally of the channel member 15.

An inner cutter indicated generally at 20 (Fig. 4) is slidably positioned within the grooves 19. The ends of the top wall 21 and side walls 22 are connected by the integrally formed, trapezoidal shaped end portions 23. The lower edges of the side walls 22 are integrally formed with the outwardly and upwardly bent clamping portions 24 of U-shaped cross section (Fig. 5) which resiliently position therewithin against the side walls 22 the oppositely disposed inner cutter blades 25 having the cutting edges 26 disposed uppermost and in complementary relationship to each other. An outer cutter is provided and comprises a slotted cylinder 27 rotatably mounted on the channel member 15 intermediate the angle brackets 13. The slotted cylinder 27 includes the thickened end portions 28 which are adapted to abut the flanges 13 to prevent longitudinal displacement of the slotted cylinder off of the channel member 15, as will be obvious, the slotted cylinder 27 and end portions 28 thereof being freely spaced from the supporting surface 12 of the handle 10 to facilitate the rotational movement thereof when moved across the skin of the shaver. The cylinder 27 is provided with the slots 29 extending over substantially the entire surface thereof, the slots 29 being arranged in longitudinally spaced sections, substantially as illustrated. As shown in Fig. 5, the cutting edges 26 are in contact with the inner surface of the slotted cylinder 27 and cooperate with the rotating cutting edges of the slots 29 to cut and shear the beard as the cylinder 27 is moved back and forth across the skin of the shaver. Due to the angle with the vertical and the complementary position of the inner cutting blades 25, it will be noted that the beard will be cut in both directions of the outer cylinder 27 on both the up stroke and down stroke, to effect an economy of time during the shaving operation. It will also be noted that the continuous contact between the cutting edges 26 of the inner cutter and the inner surface of the slotted cylinder 27 provides an automatic honing action to retain the cutting edges 26 sharp and true for long periods of time.

After the blades 25 have become worn, the inner cutter 20 may be ejected outwardly through either end of the channel 15 and slotted cylinder 27 (Fig. 1) and a new inner cutter 20 inserted (Fig. 2). The new cutter may be pushed inwardly into the grooves 19 to automatically eject the old inner cutter. Thus, the inner cutter blades 25 may be replaced in an easy and ready manner through either end of the device without the necessity of at any time having the user's fingers come

into contact with the cutting edges 26 and to prevent cuts thereby. During the shaving operation, the beard hairs will be passed inwardly through the slots 27 and moved against the stationary cutting edges 26 to cut the same with a shearing action to provide a quicker, closer shave, without the requirement of either electricity or shaving lather. The device may be carried in one's pocket and may be used on camping trips and in isolated areas without requiring either a source of power or shaving lather.

The slots 29 are symmetrically arranged and of similar shape and maybe of any suitable geometric configuration for example, they may be straight, circular, diagonal, elliptical, oval, polygonal or rhombic. The distance between the cutting edges 26 is approximately one-quarter of an inch.

It will be noted that the provision of the oppositely disposed blades 25 permits cutting on both the up and down stroke to not only effect an economy of time during shaving but to eliminate the necessity of marking the handle 10.

Referring now particularly to Fig. 6, there is shown a modified form of the present invention wherein the inner cutter 20a is provided with a pair of parallel blades 25. The inner cutter 20a includes a rectangular top wall 21a integrally formed along the oppositely longitudinal edges thereof with the parallel inclined side walls 22a against the outer surfaces of which the blades 25 are positioned. The ends of the top wall 21a and side walls 22a are connected by parallelogram-shaped end portions, not shown. The lower edges of the side walls 22a are integrally formed with the outwardly and upwardly bent clamps 24a of U-shaped cross section which resiliently retain therewithin the blades 25, the upper edges of the clamps 24a extending upwardly above the top wall 21a. In this form of the invention, the device will shave on only movement of the slotted cylinder in one direction. However, the two blades will cooperate to reduce the shaving time, as will be obvious.

In other respects, the form of the invention shown in Fig. 6 is the same as that shown in Figs. 1 through 5, and like reference numerals identify like parts throughout the several views.

While various changes may be made in the detail construction, it shall be understood that such changes shall be within the spirit and scope of the present invention as defined by the appended claims.

The top walls 21 and 21a are provided with perforations 30 and 30a respectively to permit the passage of cut hair downwardly therethrough.

The holder 24 may, of course, be used with only one blade 25 without departing from the scope of the invention as will be obvious.

Having thus set forth and disclosed the nature of my invention, what is claimed is:

1. A non-electric dry shaver comprising, in combina-

tion, a handle, a segmental cylindrical member, means mounting the opposite ends of said segmental cylindrical member upon said handle, a slotted hollow cylinder member open at both ends rotatably mounted upon said segmental circular member intermediate said mounting means, said segmental cylindrical member having a longitudinal groove defined by inwardly extending spaced parallel sides, the outer longitudinal edge of said sides defining tracks, blade holding means slidably supported upon said tracks for longitudinal movement through said cylinder, a pair of cutting blades carried upon opposite sides of said blade holding means having edges in contact with the inside surface of said cylinder, said blade holding means comprising a blade holder of trapezoidal cross section having downwardly and outwardly sloping opposite sides, outwardly and upwardly extending clamps integral with the lower longitudinal edge of said opposite sloping sides with the lower ends of said clamps slidably received within said tracks of said segmental cylindrical member, and said cutting blades extending toward each other to cut on both the upward and downward strokes of the device.

2. A non-electric dry shaver as set forth in claim 1, wherein said holding means further comprises a perforated rectangular top wall connecting the upper edge of said side walls together below said cutting edges.

3. A non-electric dry shaver according to claim 2, said mounting means comprising a pair of longitudinally spaced angle brackets, first fastening means securing the horizontal portions of said angle brackets to said handle means, and second fastening means securing the vertical portions of said angle brackets to the opposite ends of said cylindrical member below said cavity therein, the upper ends of said vertical portions terminating below said blade positioning means so as to provide clearance for the ejection of the same.

4. A non-electric dry shaver according to claim 3, said handle means comprising a handle having a semi-circular edge and a straight edge, said angle brackets mounted on said straight edge, said slotted cylinder being freely spaced from said straight edge and prevented against longitudinal displacement from said cylindrical member by the vertical portions of said angle brackets engaging the open ends thereof.
